United States Patent Office.

E. M. CHUMARD, OF PITTSTON, PENNSYLVANIA.

Letters Patent No. 74,198, dated February 11, 1868.

IMPROVEMENT IN WAGON-BRAKES.

The Schedule referred to in these Letters Patent and making part of the same.

TO ALL WHOM IT MAY CONCERN:

Be it known that I, E. M. CHUMARD, of Pittston, in the county of Luzerne, in the State of Pennsylvania, have invented a new and improved Brake for Checking or Stopping the Speed of Wagons and Cars; and I do hereby declare that the following is a full, clear, and exact description, reference being had to the accompanying drawings, and to the letters of reference marked thereon. In the annexed drawings, making a part of this specification—

Figure 1 is a side view of the hounds, brake, and wheel of the hind part of a wagon.

Figure 2 is a top view of the same, without the wheel.

Figure 3 is a drawing to show another mode of taking the power to operate the brake from the motion of the wheel.

I construct my brake with a brake-stick, C, extending from one wheel to the other, across the top of the hounds, with the usual brake-blocks, *e. e.* Along one edge of this stick I put a roller, R, with two arms, *n* *h*, at each end of the roller. The roller is attached and held firmly to the brake-stick C by two eyes, E E. The arm *h* is held from swinging by the rod *c*, connecting with hounds B. I then make a second brake-stick, F, much lighter than the first, which I connect to the arms *n* by the rods *d*, leaving the stick hang under the hounds. The second brake-stick, F, is connected to the lever *a* by the rods *b*. The brake-stick F extends from one wheel to the other, and is connected to the arms *n* at each end of the roller R. The lever *a* is connected to the roller P, which extends from one hound to the other, and has short arms, which are connected to the brake-stick F, at each end of the stick, by the rods *b*.

The brake is operated by drawing the blocks on the brake-stick F against the wheels, by pulling forward the lever *a*, and the friction caused by the rubbing of the wheels against the blocks, carries the brake-stick F downward with the wheels, which draws the arms *n* downward, and as the other arms at *h* are stationary, the roller R is thrown towards the wheels, pressing the brake-stick C against them with force. When the brake-stick F is no longer held against the wheels, the spring D throws the brake-stick C off from the wheels, and the brake ceases to take effect.

In fig. 3, the lever *a* is connected by the rods *b* to the brake-stick C, and on the lever *a* there is a slide, *m*, with a block, F, which may be drawn against the wheel by a small lever, and the friction of the wheel, rubbing against the block F, will carry the lever *a* forward, and draw the brake-stick C, with its blocks, against the wheels. By thus applying the circular motion of the wheels to operate the brake, it is done with much less effort on the part of the brakeman.

Having thus fully described my invention, what I claim as new, and desire to secure by Letters Patent, is—

1. The arrangement of the roller R with the arms *n* and *h*, and the brake-bar F, when constructed in the manner substantially as and for the purposes herein specified.
2. The slide *m*, constructed as described, and used with the brake-bar F, in the manner substantially as and for the purposes set forth.

E. M. CHUMARD.
